UNITED STATES PATENT OFFICE

JOHN GELOSO, OF LAWRENCE, MASSACHUSETTS, ASSIGNOR TO PILOT RADIO & TUBE CORPORATION, OF LAWRENCE, MASSACHUSETTS, A CORPORATION OF DELAWARE

DESIGN FOR A CABINET FOR RADIORECEIVERS

Application filed February 17, 1931. Serial No. 38,706. Term of patent 3½ years.

To all whom it may concern:

Be it known that I, JOHN GELOSO, a citizen of Lawrence, in the Commonwealth of Massachusetts, county of Essex, have invented a new, original, and ornamental Design for a Cabinet for Radioreceivers, of which the following is a specification, reference being had to the accompanying drawing, forming part thereof.

The figure is a perspective view of a radio cabinet showing my new design.

I claim:

The ornamental design for a cabinet for radioreceivers, as shown.
